UNITED STATES PATENT OFFICE.

EMILE BLUME, OF HARBURG-ON-ELBE, GERMANY.

EXHAUST-PIPE NOZZLE FOR LOCOMOTIVES.

Application filed November 3, 1925. Serial No. 66,568.

To all whom it may concern:

Be it known that I, EMILE BLUME, a German citizen, residing at 1. Wilstorferstrasse 3, Harburg-on-Elbe, Germany, have invented certain new and useful Improvements in or Relating to Exhaust-Pipe Nozzles for Locomotives (for which I have filed application in Germany, July 14, 1924), of which the following is a specification.

- 10 This invention relates to exhaust pipe nozzles for locomotives and other similar engines wherein the exhaust steam is utilized when required for promoting a draught in the chimney or smoke-stack of the engine 15 in order to increase the intensity of the action of the furnace and consequently the steam production of the boiler. The object of the said invention is to enable the reinforcement of the chimney draught by the 20 exhaust steam to be regulated over a range between zero and the maximum efficiency obtainable, and thus to adapt the production of steam to the actual steam requirement of the engine, and consequently to the engine 25 efficiency.

Arrangements for varying the action of the exhaust pipe nozzle are known, which in one form enable the entire exhaust flow to be conducted either into the chimney, or into 30 the open air; and in another form the exhaust issuing from one engine cylinder is conducted through the exhaust pipe nozzle into the chimney, while the exhaust issuing from the other engine cylinder is conducted 35 through a separate pipe into the open air, or alternatively both exhausts can be allowed to pass through the exhaust pipe nozzle into the chimney. The first arrangement therefore only admits of the maximum exhaust 40 pipe inducing action or prevents all such action entirely. The latter arrangement, on the other hand, only allows of maximum or half exhaust pipe action. No account is taken in either of the two arrangements of 45 intermediate degrees of action. The last-mentioned arrangement, moreover, has at times a defect in so far as it possesses as a reversing organ, a rotary slide valve which in the event of its being brought to intermediate positions between the terminal positions 50 mentioned, must set up throttling of the issuing steam and consequently a prejudicial counter-pressure on the working piston, whereby the engine efficiency is 55 reduced.

According to this invention means are provided for controlling the admission of exhaust steam to the chimney whereby such exhaust steam can at will be entirely passed into the chimney, entirely diverted therefrom, or admitted therein to any intermediate extent, the cross-sectional area of the orifices through which the exhaust steam passes being in all positions equivalent to the cross-sectional area of the exhaust pipe 60 or pipes so that no throttling of the exhaust steam takes place.

In an embodiment of the invention, an annular nozzle-shaped exhaust pipe header is provided with an incorporated regulating 70 valve, which in a terminal position closes the exhaust pipe sector and provides an outlet leading to a separate pipe, whilst, in the other terminal position, it opens an annular outlet to the chimney but closes the orifice 75 leading to the separate outlet pipe. In the possible intermediate positions, both orifices are partly free, so that a part of the engine exhaust escapes into the chimney and a part through the separate outlet pipe, in which 80 connection the sum of the cross-sections of the orifices is so calculated, that no throttling takes place and the opening of one orifice is reduced in the measure by which that of the other is increased.

In another embodiment of the invention, the annular outlet to the chimney from the interior of the exhaust pipe header may be eliminated. The exhaust pipe, acting in the usual manner, is in such an event contained 85 in a housing, which may be connected with the outer air by means of a separate steam outlet pipe, and, according to the position 90 of the regulating organ fitted in the exhaust pipe header, allows the whole of the exhaust steam to escape whereby all fire stimulating action is discontinued, or only allows a part 95 of the exhaust steam to escape to the atmosphere whilst the other part passes through the exhaust pipe header, setting up at the 100 same time the fire stimulating draught, or finally the outlet to the atmosphere is absolutely shut off, so that the entire exhaust 105 escapes through the exhaust pipe header into the chimney. Further the principle of the invention may also be carried out by connecting a separate steam outlet pipe to each 110 of the exhaust pipes coming from the steam cylinders and meeting in the exhaust pipe header, and by introducing throttle valves

at the point where the steam outlet pipes are united with the exhaust pipes, which valves each allow one of the two pipes to be shut off towards the exhaust opening.

In the accompanying drawings are illustrated three constructional examples of the invention.

Figure 1 is a section through a part of the smoke box of a locomotive provided with the arrangement according to the invention, the regulating valve in the annular nozzle-exhaust pipe being illustrated in the position in which it closes the annular outlet orifices towards the exhaust pipes and permits the latter to communicate with a separate steam outlet pipe.

Figure 2 is a section taken in a position at right angles to that in Figure 1 through the exhaust pipe header, with its regulating valve lowered to open the annular orifices which place the exhaust pipes in communication with the chimney and close the inlets leading to the separate steam outlet pipe.

Figure 3 is a section illustrating a modification of the arrangement represented in Figure 1, wherein the central space in the exhaust pipe header serves for the outlet of the exhaust steam into the chimney, whilst the annular space surrounding the exhaust pipe header is connected with the open air by means of a separate steam outlet pipe.

Figure 4 is a section taken at right angles to that seen in Figure 3.

The exhaust pipes *a*, *a'* which receive the exhaust steam from the working cylinders of the engine, meet in the housing *b*, on which is placed the exhaust pipe header *c*, the perpendicular centre line of which coincides with that of the chimney *d*. In the construction represented in Figures 1 and 2, the annular nozzle exhaust pipe header *c* has concentric orifices *e* outside the wall of the header which encloses a central cylindrical chamber *f*; to the top of this wall is connected a steam outlet pipe *g*, which as illustrated may ascend in the centre of the chimney or flue *d*, but which can alternatively be located in any other convenient position in relation to the chimney. The regulating valve *h* comprises a hollow cylindrical guide piece projecting into the chamber *f* and a flange *i* having bevelled or conical edges adapted to engage counterpart surfaces on the header *c*. The bottom of the regulating valve *h* is suitably arched upwards and a rod *k* is secured therein, by means of which rod *k* the upward and downward movements of the valve *h* are effected. In the wall of the regulating valve *h* are orifices *l* through which, in the position shown in Figure 1, the steam exhausted through the pipes *a*, *a'* from the cylinders passes into the interior of the regulating valve *h* and thence into the steam outlet pipe *g*, through which it escapes into the open air. An annular

wall *m* of the housing *b* serves as a guide for the regulating valve *h* and is of such dimensions that it closes the orifices *l*, when the regulating valve is in its lowest position, as seen in Figure 2. A base plate *n* closes in the bottom of the housing *b* while permitting vertical movement of the rod *k* which passes through the said plate.

In the modification represented in Figures 3 and 4, the annular space *o* surrounding the exhaust pipe header, is closed towards the top, the orifices *e* being eliminated, and the steam outlet pipe *g* is connected to one side of this chamber *o* as seen in Figure 4, the said pipe *g* being then turned upward outside the chimney *d*.

In the supposed case of a locomotive driven at high speed, if the generation of steam in the boiler becomes so great, in consequence of intense draught through the furnace resulting from the powerful action of the exhaust pipe, that it exceeds the steam requirement, and the safety valves blow off, the regulating valve *h* is brought into the position seen in Figure 1 by the operation of a handle or by the use of some other suitable actuating arrangement (for example, by compressed air).

The steam escaping from the cylinders of the engine then passes through the steam outlet pipe *g* into the open air, and the orifices *e* in the header *c* are cut off from the interior of the valve *h* by the closing of the valve formed by the flange *i*. This position may also be taken as suitable for the regulating valve when the locomotive is pulling up, as the conveyance of soot from the smoke box is thus prevented, which soot uniting with the precipitated water forming in the cool cylinders is calculated to foul the glass roofs of railway stations and is also often regarded as a nuisance by people congregated on the platforms, and has frequently given occasion for claims for damages against the railway companies in respect of soiled articles of wearing apparel. Moreover, the emission of flying sparks, often a cause of danger, is thus avoided.

In the course of the journey, should an intense inducing action of the exhaust pipe be desired, the regulating valve is brought into the position seen in Figure 2. In this position, the orifices *l* in the body of the regulating valve are closed by the cylindrical wall *m* of the housing *b*; hence no passage of the exhaust steam into the interior of the regulating valve and consequently into the steam outlet pipe *g* takes place, the whole of the exhaust passing away through the orifices *e* of the header *c*, which orifices are left open with the regulating valve in this position, in order to escape through the chimney *d*, and the exhaust steam carries along with it the air in the smoke box, whereby powerful stimulat-

ing of the fire is effected by the fresh air entering through the grate openings of the fire box. According to need, every desirable intermediate position between the two 5 terminal positions illustrated can be given to the regulating valve. In such an intermediate position the steam escapes partly through the orifices *e* of the exhaust pipe header and partly through the orifices *f* of the 10 regulating organ and the pipe *g*. It is a practical possibility of this arrangement to enlarge one of these ways and to reduce the other simultaneously. The orifices serving for outlet of the exhaust, are always proportionate to the cross-section of the 15 exhaust pipes, so that throttling of the steam cannot take place in any position of the regulating valve *h*.

The method of working with the arrangement according to Figures 3 and 4 is essentially similar, but when the regulating valve is raised, as seen in Figure 3, the exhaust steam reaches the chimney through the upper nozzle-shaped hollow cone of the 25 exhaust pipe header *c*, whereby the induced draught for stimulating firing ensues, but when the regulating organ is in the lower position, as seen in Figure 4, the exhaust passes to the intervening space *o* and thence 30 through the steam outlet pipe *g* without setting up any induced draught.

In both the modifications, the exhaust steam conveyed through the steam outlet pipes *g* can be passed through a feed water heater before its escapes into the open air, in order that the heat still contained in it 35 may be given off to the boiler feed water.

The invention is not restricted to the examples given, as many variations of design 40 may be employed within the scope of the invention.

What I claim and desire to secure by Letters Patent of the United States is:—

1. In devices for controlling the admission 45 of exhaust steam to the chimneys of locomotives and other similar engines, the combination with two steam exhaust pipes, of a header connecting said pipes and comprising a valve chamber and an upwardly directed nozzle concentrically located in the chimney and including two concentric passages, an escape pipe connected to the nozzle and forming a continuation of one 50

of said passages, and a valve adapted to reciprocate in the nozzle and cause the exhaust pipes to communicate with either or both the concentric passages of the nozzle. 55

2. In devices for controlling the admission of exhaust steam to the chimneys of locomotives and other similar engines, the combination with two steam exhaust pipes, of a header connecting said pipes and comprising a valve chamber and an upwardly directed nozzle concentrically located in the chimney and including two concentric passages, an escape pipe connected to the nozzle and forming a continuation of one of said 60 passages, and a tubular sleeve valve mounted to reciprocate within the inner of said passages in the nozzle and provided with lateral 65 ports, adapted to establish communication between said inner passage and the exhaust pipes, and with an annular skirt adapted to control passage of steam from the exhaust pipes to the outer nozzle passage. 70

3. In devices for controlling the admission of exhaust steam to the chimneys of locomotives and other similar engines, the combination with two steam exhaust pipes 75 of a header connecting said pipes and comprising a valve chamber and an upwardly directed nozzle concentrically located in the chimney, an escape pipe projecting upwardly from said nozzle and extending above the mouth of the chimney, an annular 80 nozzle chamber concentrically surrounding said valve chamber and having apertures opening into the chimney, a valve seating below said nozzle chamber, a valve housing, a valve vertically movable in said valve 85 chamber and said housing, said valve having valve faces adapted in the fully raised position of the valve to be pressed on said valve seating to cut off said nozzle chamber from said valve chamber, and also having 90 inlets which in the fully lowered position of the valve are covered by the wall of said housing, said valve faces and inlets being so spaced that in any intermediate 95 position of the valve said exhaust pipes are in communication with said valve chamber and escape pipe through said inlets and also in direct communication with said nozzle chamber. 100

EMILE BLUME.
